WEFT REPLENISHING LOOM

Benjamin W. Brouwer, Auburn, and Walter A. Patterson, Worcester, Mass., assignors to Crompton & Knowles Loom Works, Worcester, Mass., a corporation of Massachusetts

Application April 14, 1942, Serial No. 438,914

23 Claims. (Cl. 139—232)

This invention relates to improvements in weft replenishing looms and it is the general object of the invention to provide mechanism whereby a shuttle can be replenished from a plurality of stacks of reserve bobbins.

One form of the usual multicolor weft replenishing loom employs four stacks of reserve bobbins to replenish each of four shuttles carrying four different types of weft corresponding to the stacks of reserve bobbins. It is occasionally desirable to use a loom provided with this type of mechanism for weaving a fabric with two shuttles, and utilize the full capacity of the magazine to replenish the shuttles. It is an important object of our present invention to provide means whereby each of two shuttles can be replenished by bobbins drawn from a pair of stacks of reserve bobbins.

Multicolor weft replenishing magazines ordinarily employ cradles controlled by vertical slides or releasers which are reciprocated by a color slide or releaser actuator movable longitudinally into register with the slides one at a time and having also rocking motions in opposite directions to reciprocate the releasers. It is customary to give the color slide four different positions when four stacks of reserve bobbins are used in the magazine. It is another object of our present invention to provide means for giving the color slide only two positions, one for each of the weaving shuttles, and alter the releasers so that two of them can be moved when the color slide is in one of its two positions. By this arrangement a simple connection can be provided between the box motion and the color slide while at the same time full advantage can be taken of the capacity of the magazine.

When two stacks of bobbins are assigned to a shuttle as in the present instance it is desirable that successively released bobbins be derived from different stacks in order that the pair of stacks may be depleted uniformly as successive replenishing operations of the loom occur. It is a further object of our invention to provide means whereby successive releasing operations with respect to any pair of reserve stacks shall take place with respect to alternate stacks of the pair. This result is achieved by changing the relative positions of the actuator with respect to the releasers after each operation of the latter, preferably by rocking mechanism operated by the releasers.

It is a more particular object of our invention to provide the releaser slides with pivoted lugs which can be moved into and out of the path

of operative movement of actuator, and control the pivoted lugs so that they are alternately in the path. This latter result may be achieved by means of a lug positioner which changes its position each time a reserve bobbin of the associated pair of stacks moves toward transfer position.

While the invention will be set forth as applicable to two shuttles and two pairs of bobbin stacks, certain features of the invention can be used with but one pair of bobbin stacks when a single shuttle is used, or when the pattern is such that two or more transfers may occur while a single band in the pattern is being woven by one shuttle.

With these and other objects in view which will appear as the description proceeds, our invention resides in the combination and arrangement of parts hereinafter described and set forth.

In the accompanying drawings, wherein a convenient embodiment of our invention is set forth,

Fig. 1 is a front elevation of a loom made according to our present invention,

Fig. 2 is an enlarged end elevation of the magazine looking in the direction of arrow 2, Fig. 1.

Figs. 3 and 4 are detailed enlarged views of a portion of Fig. 2 showing the bobbin releasers and parts associated therewith in different positions.

Fig. 5 is a vertical section on line 5—5 of Fig. 3, parts being omitted.

Fig. 6 is a horizontal section on line 6—6 of Fig. 3 showing diagrammatically the releaser depressing lugs and the relation which they sustain to their actuators when the front pair of stacks of the magazine can supply a reserve bobbin,

Fig. 7 is a view similar to Fig. 6, but showing the position of the actuation when the rear pair of stacks can supply a reserve bobbin,

Fig. 8 is an enlarged rear elevation looking in the direction of arrow 8, Fig. 3 showing one of the pivoted lugs,

Fig. 9 is a detail horizontal section on line 9—9, Fig. 3; and

Fig. 10 is a side elevation looking in the direction of arrow 10, Fig. 8, with portions of the adjacent bobbin releaser added.

Referring particularly to Figs. 1 and 2, a loom frame 10 supports a lay 11 which is reciprocated backwardly and forwardly in the usual manner by means of connectors 12. In the present instance the left hand end of the loom is provided

with a gang G of shuttle boxes having upper and lower boxes 14 and 15, respectively, connected to a box lifter rod 16 surrounded by a lifting spring 17. The lower end of the latter engages the top of a sleeve 18 which slides vertically in a rocker foot 19 mounted on the usual rocker shaft 20 about which the lay rocks. Rod 16 passes through sleeve 18 and a box lifter chain 21, connected to the sleeve 18, is trained over lay carried sheaves 22 and then down around a sheave 23 rotatable on the loom frame. The chain then extends upwardly around a sheave 24 on the loom frame and is connected to a box motion designated generally herein at 25. The invention is more particularly applicable to the so-called Knowles loom although it is not limited in its uses to this type of loom. Such a loom is provided with a head K which includes the box motion 25, and has upper and lower multi-lated cylinders 28 and 29 rotating in opposite directions as usual to move a vibrator gear 30 either in a right or left hand direction, depending upon its vertical position as determined by the pattern chain 31. The mechanism 25 is connected to the vibrator gear and raises and lowers the gang G so that either of its shuttle boxes can be in active position for the picking of the shuttles S1 and S2 in boxes 14 and 15, respectively.

In the present instance the opposite or right hand end of the loom as viewed in Fig. 1 is provided with a single shuttle box 35 which receives the shuttles S1 and S2 one at a time when they are picked from the gang G. A weft replenishing mechanism of the multicolor type designated at M is mounted on the loom frame over the shuttle box 35 and except for certain modifications to be pointed out hereinafter may be made in the usual manner and be similar to the mechanism shown in prior Patent No. 1,030,748. Mechanism M comprises inner and outer plates 37 and 38 between which are located in the present instance four stacks of reserve bobbins B1, B2, B3 and B4.

As shown in Fig. 2 the lower end of each stack of bobbins is provided with a releasing cradle 40 normally empty and controlled as to its angular position by a vertically movable bobbin releaser. The slides are indicated herein at 41, 42, 43 and 44 and correspond respectively to the stacks B1, B2, B3 and B4. The slides are normally down but are raised by mechanism to be described hereinafter so that their corresponding cradles may be rocked to receive a bobbin and move it toward transfer position. Subsequently the raised slide is lowered to rock the cradle reversely to discharge the bobbin and let it fall to the transfer position designated at B, Fig. 2, for transfer into whichever shuttle is in box 35.

When a slide rises a dog 45 pivoted on its upper end moves over a shelf 46 secured to a top shaft 47 rockably mounted on plate 31. When the raised slide is later depressed its dog engages the shelf to rock shaft 47 in a clockwise direction, see Fig. 1, causing depression of a rod 48 to lift transfer latch 49 into the path of a bunter 50 mounted on the lay. At the same time rod 51 is raised to rock the shuttle position detector and thread cutter mechanism 52 in a clockwise direction as viewed in Fig. 2 around its pivot 53. When the transfer latch is raised and the shuttle position detector is in rear position the magazine is set for transfer and this condition is created by depression of a previously raised slide. As the lay advances the

transferrer arm 55 is lowered in usual manner to insert the bobbin in the transfer position B into the shuttle in shuttle box 35.

A selector lever 60 is pivoted as at 61 with respect to the plate 37 and is normally held in the full line position shown in Fig. 2 by the spring 62. A flexible connector 63 attached to lever 60 extends across the loom and is attached to the chain 21 in such a way that the lever is in the full line position shown in Fig. 2 when box 14 and shuttle S1 are active, but when the chain 21 moves to raise the gang G and place box 15 and shuttle S2 in active position the lever 60 will move rearwardly to the dotted line position shown in Fig. 2. This latter part of the construction is similar to that which has been employed heretofore when two shuttles have been replenished from a two-stack magazine, one stack for each shuttle.

The upper end of lever 60 is connected to a rod 68 horizontally slidable on the frame 37 and having secured thereto an actuator 69 having a web 70 which is operatively connected to the upper end of a rod 71. The lower end of rod 71 is connected to a floating lever 72 mounted on the upper end of a vertically reciprocable head 73 on the top of a rod 74 which extends downwardly for actuation by a lever 75. A cam 76 on the bottom shaft 77 of the loom rocks the lever 75, causing the floating lever to move downwardly on detecting beats of the loom when a shuttle occupies box 35 and the lay is in front center position. Whether rod 71 is depressed at this time depends upon the condition of weft in the box 35 as determined by a detector D. If sufficient weft for continued weaving is present lever 72 moves downwardly without affecting rod 71, but if the shuttle in box 35 is depleted of weft the normal motion of the floating lever 72 is interrupted and rod 71 is lowered to cause a rocking of shaft 68 in a counter-clockwise direction as viewed in Fig. 1. After the shuttle in box 35 has been picked to the opposite side of the loom and time has been allowed for shifting gang G, cam 76 acts to raise floating lever 72 and cause upward motion of rod 71 the result of which is to give the shaft 68 a reverse rocking in a clockwise direction as viewed in Fig. 1. This latter rocking of the shaft 68 occurs every other pick of the loom subsequent to box shifting period and is not dependent upon the condition of weft in the shuttles. It is this second rocking of shaft 68 which causes downward motion of the vertical slides to set the magazine for transfer as already described.

The matter thus far described except as noted hereinafter is of common construction and operates in the usual manner. The pattern chain 31 can be built to cause shifting of box gang G every second pick of the loom so that the shuttles S1 and S2 are active in alternation each for two successive picks, or the shuttles can be active for longer periods of successive picks if it is desired to weave a fabric having relatively wide stripes. The shuttles S1 and S2 can carry distinctive weft if desired or can both carry the same general type of weft, in which case all the bobbins in the magazine M will be of the same kind.

In carrying our present invention into effect we provide means by which stacks B1 and B2 can provide reserve bobbins alternately for successive replenishments of shuttle S1 and by which the rear stacks B3 and B4 can similarly provide bobbins for the replenishment of shuttle S2. The actuator 69 has front and back horizontally

extending actuator arms 80 and 81, respectively, which are provided for the front and back pairs of vertical slides. The vertical slides 41 and 42 are provided each with an integral depressing lug 82, both of which lie under arm 80 when the actuator is in forward position corresponding to the full line position shown in Fig. 2. The rear pair of vertical slides 43 and 44 are similarly provided each with an integral lug 83 which lies under the arm 81 when the actuator is in the rear position corresponding to the dotted line position of lever 60 in Fig. 2. It is to be understood that the arms 80 and 81 are alternately operatively related to their pairs of lugs 82 and 83, respectively.

An important feature of our present invention resides in replacing the usual upper lugs on the vertical releaser slides by pivoted lugs which are movable into and out of the path of the actuator arms 80 and 81 when the latter move upwardly incident to indication of weft exhaustion. As shown in Figs. 3 and 4 the slides 41, 42, 43 and 44 are provided, respectively, with pivoted lugs 91, 92, 93 and 94. These lugs move about their pivots 90 on the vertical slides and each is provided with a lifting finger 95 having a lower lifting surface 96 for engagement with its actuator arm. Each of the pivoted lugs is also provided with a surface 97 which is inclined downwardly and away from the corresponding pivot 90 to terminate at a point below the pivot. Furthermore, each of the pivoted lugs is provided with a stop 98 for engagement with a part 99 of the corresponding vertical slide. There is some slight variation between the different pivoted lugs but each is provided with the parts already described so that when the pivoted lug is in working position its surface 96 will be horizontal and over the corresponding actuator arm with the associated stop 98 engaging some part of its vertical slide. Each pivoted lug is counterweighted and tends to hold its finger 95 horizontal and its stop in engagement with the associated slide. The stops are so located as to assist by their weight to hold their lugs in normal position. Unless acted upon by mechanisms to be described hereinafter, therefore, the lugs tend to move to operative position with respect to their actuator arms and when in this operative position are capable of causing upward motion of their corresponding vertical slides when lifted.

Each pair of vertical slides is associated with a positioner for the corresponding pivoted lugs. The purpose of each positioner is to permit but one pivoted lug of the associated pair to be operatively related to the corresponding actuator arm at a time. Since the front and back positioners 103 and 104, respectively, are similar, the details of but one of them will be set forth, namely, that for the front pair of slides.

The positioner 103 comprises a four-armed rocking lever having front and back horizontal arms 105 and 106, respectively, and a vertical arm 107. A stud 108 carried by a bracket 109 secured on the frame 37 is located preferably midway between the vertical paths of travel of the slides 41 and 42 and affords a pivot around which the positioner 103 rocks. The arm 105 is positioned for engagement with vertical slide 41 when the latter rises, and in similar manner arm 106 is engaged by vertical slide 42.

The fourth arm 110 of positioner 103 extends downwardly and is secured to a depending spring 111 the lower end of which may be broadened at 112 for engagement with the lifting fingers 95

of the pivoted lugs 91 and 92. In order that the lower ends of the positioning spring 111 may be retained yieldingly either in right or left hand position as viewed in Figs. 3 and 4, we provide a flat spring 115 extending over a stud 116 carried by the bracket 109. The front end of spring 115 extends under a pressure pin 120 on bracket 109 and then extends forwardly to engage the upright arm 107. In a similar manner the rear end of the spring 115 extends under a second pressure pin 121 and then projects rearwardly to engage the arm 107 of the rear positioning lever 104. The point of engagement between the spring and the positioning lever will normally be either to the right or the left of a vertical line passing through the pivot stud 108, and the spring 115 therefore serves to hold each positioner in either of its two positions. A crimp 117 on each end of the spring 115 assists in definitely locating the corresponding positioner. Bolts 118 may be used to hold the bracket 109 in position on magazine plate 37.

In operation, the actuator rod 68 is moved backwardly and forwardly as already described to locate the arms 80 and 81 in either of two operating positions. When shuttle S1 is active and the actuator 69 is in the front position, arm 80 can cooperate with the lugs of the front pair of vertical slides 41 and 42 while the rear arm 81 is out of operating relation with respect to its lugs 43 and 44. When there is a shift of the gang G to render shuttle S2 in box 15 active, arm 80 will move rearwardly out of register with its lugs and the arm 81 will move to operative position with respect to the lugs on the slides 43 and 44. The actuator 69 is therefore seen to have but two positioners, one for each pair of bobbin releasing vertical slides.

Assuming that the magazine is in the condition shown in Figs. 2 and 3 and that shuttle S1 is temporarily active, arm 80 will be moved to its forward operating position over and in register with the bottom lugs 82, as shown in Fig. 6. The positioner spring 111 of positioner 103 under this assumption has been rocked to the right to turn lug 91 to the inoperative full line position shown in Fig. 3. Pivoted lug 92 is therefore free to swing to the operative full line position shown in Fig. 3 with its arm 95 over the actuator arm 80. For convenience the same condition is assumed to exist in Fig. 3 for the rear pair of vertical slides 43 and 44 and their positioner 104.

Since shuttle S1 is active the arms 80 and 81 will be in the position indicated in Figs. 3 and 6, and if there is sufficient weft for continued weaving in this shuttle the fingers will remain unmoved when the detector D performs its detecting function when shuttle S1 is at the magazine end of the loom. If, however, the shuttle is depleted of weft arm 80 will rise as already described and in doing so will engage lug 92 with resultant upward motion of slide 42. As the latter slide nears the upper limit of its motion it will engage arm 106 of the positioner and rock the latter from the full to the dotted line position of Fig. 3. The positioner will always be free to rock in this direction because under these conditions the other vertical slide 41 of the pair will be down and will not interfere with lowering of arm 105. When the positioner 103 rocks the spring 111 moves rearwardly to the left position of Fig. 3 and engages the inclined surface 97 of lug 92. As soon as arm 80 moves downwardly from its high position spring 111 will rock lug 92 to the dotted position shown in Fig. 3 out of operative position with respect to the arm 80. Simultaneously, the front lug 91

will rock to the dotted operative position of Fig. 3, or the full line position of Fig. 4, so that its lifting finger 95 will be over arm 80.

The next time shuttle S1 requires replenishment arm 80 will rise and engage lug 91 to lift the front slide 41. As the latter reaches its high position the positioner 103 will again be rocked, this time to the left, and the spring 111 of positioner 103 will effect a reversal in the relation of the lugs 91 and 92 with respect to arm 80. It is to be understood that one of the regularly recurring down motions of arm 80 which occurs at two-pick intervals will always occur between the successive detecting operations of the detector D, hence when either of the slides 41 or 42 is in raised position it will be lowered by an engagement of the arm 80 with one or another of the lugs 82 before the other vertical slide of the pair can rise.

It will thus be seen that successive replenishments of shuttle S1 cause alternate rising of the slides 41 and 42. The effect of this alternation in the actuation of the vertical slides is to cause the reserve bobbins of the corresponding stacks to be delivered in a regular order so that neither stack becomes depleted while any considerable number of reserve bobbins remain in the other stack of the same pair.

It is not believed necessary to describe in detail the operation of the rear pair of vertical slides and the positioner 104 and their pivoted lugs 93 and 94. Whenever the gang G is in position to render shuttle S2 active actuator arm 81 will be in rear position, see Fig. 7, and operatively related to its pair of releasing slides. The positioner 104 will operate in a manner similar to that already described in connection with positioner 103 to cause alternate rising of the slides 93 and 94 for successive replenishments of the shuttle S2.

It is customary in weft replenishing mechanisms of the general type set forth herein to provide means for holding the bobbin releaser slides in their normal low and temporary high positions. In Fig. 9 we show the customary spring plungers used for this purpose and the manner in which they are mounted. The magazine plate 37 is provided with guide lugs 125 for the vertical slides and a block 126, one for each pair of releaser slides, is held by bolts 127 to certain of the guides 125. The block has slidable therein a plunger 128 for each vertical slide and each plunger has a head 129 to enter top and bottom notches 130 and 131, respectively, of the associated releaser slides. Each plunger is surrounded by a compression spring 132 which urges the plunger head 129 into one or the other of the notches of the corresponding vertical slide. That part of the block 126 adjacent to the plate 37 is spaced from the latter to define an opening 135 through which the spring 132 extends.

The relation between the springs 111, 115 and 132 is such that the positioners will be held as already described. When an actuator arm raises one of the pivoted lugs the corresponding releaser slide engages the associated positioner to rock the latter and move its spring 111 against the rising pivoted lug. As the actuator arm starts down after reaching its high position the plunger head will be in the bottom notch 131 and will hold the releaser slide up and will cooperate with spring 115 to prevent the spring 111 from turning its positioner in a direction to lower the raised releaser slide. This condition is due to the fact that the action of springs 115 and 132 is stronger than that of spring 111. When the actuator arm moves down away from the raised pivoted lug, the

spring 111 moves toward the corresponding releaser slide to rock the pivoted lug to inactive position. The spring 111 will always be under some strain tending to move the associated positioner toward a neutral position, but the spring 115 will be strong enough to resist this tendency.

If the loom is adapted for the weaving of a single color fabric in which the weft is to be mixed by two shuttles, actuator arm 80 will be aligned with the front pair of release slides on the first pair of picks, arm 82 will be registered with the back pair of releaser slides for the second pair of picks, arm 80 will again be registered with the front pair of slides for the third pair of picks etc. When operated in this way both shuttles are active for approximately the same number of picks, and since each shuttle is replenished by bobbins drawn alternately from the corresponding stacks, substantially the full capacity of the magazine may be utilized before the bobbin attendant need again fill the magazine. If, on the other hand, the loom is weaving a fabric having two types of weft, the pattern may require two picks of one color followed by two picks of the other color and the magazine will become empty as already described. Each shuttle will be replenished by bobbins drawn from its own pair of stacks, and the pairs will therefore carry reserve bobbins of different types. If two different colors are used and the pattern makes uneven demands on the two shuttles, the shuttle S1 to be more active than shuttle S2 for instance, the front pair of reserve bobbins will become depleted before the rear pair, but shuttle S1 will be replenished from the full capacity of the front pair of stacks.

From the foregoing it will be seen that we have provided a weft replenishing loom operating with two shuttles each of which can be replenished from a pair of stacks of reserve bobbins, and that the bobbins from either pair are drawn alternately from the stacks for successive replenishments of the corresponding shuttle. It will also be seen that the bobbin releaser slides are provided with pivoted lifting lugs which are moved into and out of the path of the actuator arms 80 and 81. The force for operating the positioners 103 and 104 is derived from the actuator fingers 80 and 81 and transmitted through the releaser slides. Each shuttle has its own pair of stacks and for this reason the shuttle S1 and S2, may if desired, be provided with different wefts and the associated stacks provided with corresponding reserve bobbins. Furthermore, the position of the pivoted lugs on either pair of releaser slides is independent of the lugs of the other pair of slides, and for this reason one shuttle may be more active than the other without interrupting the order of delivery of the bobbins from their stacks. While we have shown the upper lugs pivoted to their slides we do not necessarily wish to be limited to this construction, inasmuch as it is sufficient if the pivoted lugs are alternately operative and cooperate with actuator fingers to advance a bobbin toward transfer position.

Having thus described our invention it will be seen that changes and modifications may be made therein by those skilled in the art without departing from the spirit and scope of the invention and we do not wish to be limited to the details herein disclosed, but what we claim is:

1. In a weft replenishing loom operating with two shuttles which are alternately active, a pair of stacks of reserve bobbins for each shuttle, a bobbin releaser for each stack, an actuator com-

mon to the releasers, means to move the actuator from the releasers of one pair of stacks to the releasers of the other pair of stacks when there is a change in the active shuttle, and releaser selector mechanism to cause the actuator to operate the releasers of either pair of releasers one at a time and alternately for successive replenishments of the corresponding shuttle.

2. In a weft replenishing loom having two stacks of reserve bobbins for the replenishment of a shuttle, a bobbin releaser for each stack to have a movement in a given direction to advance a bobbin of the corresponding stack toward replenishing position, an actuator for said releasers to move in said given direction preparatory to a replenishing operation of the loom upon exhaustion of weft in the shuttle, and selector mechanism operated by said releasers to cause alternate movements of said releasers in said given direction by successive movements of said actuator in said given direction.

3. In a weft replenishing loom having two stacks of reserve bobbins for the replenishment of a shuttle, a bobbin releaser for each stack movable to advance a bobbin of the corresponding stack toward replenishing position, an actuator to move in a given direction preparatory to a replenishing operation of the loom upon exhaustion of weft in the shuttle, and selector mechanism operated by a force derived from the actuator to cause the latter by successive movements thereof in said given direction to move the releasers alternately.

4. In a weft replenishing loom having two stacks of reserve bobbins for the replenishment of a shuttle, a bobbin releaser for each stack, each releaser when moved being effective to advance a bobbin of the corresponding stack toward transfer position, an actuator for the releasers movable in a given direction preparatory to a replenishing operation of the loom upon exhaustion of weft in the shuttle, and selector mechanism operated by a force derived from the actuator and transmitted through said releasers to cause said actuator by successive movements thereof in said given direction to move the releasers alternately.

5. In a weft replenishing loom having two stacks of reserve bobbins for the replenishment of a shuttle, a bobbin releaser for each stack, each releaser to have a movement to advance a bobbin of the corresponding stack toward replenishing position, an element on each releaser by which the latter is moved, an actuator moving in a given direction preparatory to a replenishing operation of the loom to engage one or the other of said elements to give the aforesaid movement to the corresponding releaser, and selector mechanism operated by each releaser when having said movement by engagement of said actuator with the corresponding element to change the relation of said elements and actuator to cause the latter on the next movement thereof in said given direction to move the other element and releaser therefor.

6. In a weft replenishing loom having a frame supporting two stacks of reserve bobbins for the replenishment of a shuttle, a bobbin releaser for each stack to have a movement to advance a bobbin of the corresponding stack toward replenishing position, an actuator for said releasers moving in a given direction to effect said movement of the releasers when weft exhaustion is indicated in the shuttle, a positioner pivoted on the frame for movement to two different posi-

tions by said releasers when the latter have said movements alternately, a lifter element on each releaser to be engaged by the actuator when the latter moves in said given direction, means tending to move each element into the path of said actuator when the latter moves in said given direction, said actuator normally registered with but one of said elements at a time and when engaging the element registered therewith causing the corresponding releaser to rock the positioner from one position to another position, said positioner when moving to said other position moving the last named element out of register with said actuator and the means corresponding to the other element moving the latter into registry with the actuator.

7. In a weft replenishing loom operating with a shuttle to be replenished by bobbins drawn from two stacks of reserve bobbins, a bobbin releaser for each stack movable in opposite directions to effect bobbin release, an actuator movable in one direction preparatory to a replenishing operation of the loom to effect lifting of a releaser and movable regularly in the opposite direction to effect lowering of a raised releaser, a depressing lug on each releaser normally below the path of said actuator when the latter moves in said opposite direction but movable into said path when the corresponding releaser is raised, a lifting lug movably mounted on each releaser, and means to cause said lifting lugs to move alternately into the path of said actuator when the latter has successive movements in said one direction.

8. In a weft replenishing loom operating with a shuttle to be replenished by bobbins drawn from two stacks of reserve bobbins, a bobbin releaser for each stack movable in opposite directions to effect bobbin release, an actuator movable in one direction preparatory to a replenishing operation of the loom to effect lifting of a releaser and movable regularly in the opposite direction to effect lowering of a raised releaser, a depressing lug on each releaser normally below the path of said actuator when the latter moves in said opposite direction but movable into said path when the corresponding releaser is raised, a lifting lug movably mounted on each releaser, and means operated by said releasers one at a time to cause said lifting lugs to move alternately into the path of said actuator when the latter has successive movements in said one direction.

9. In a weft replenishing loom operating with a shuttle to be replenished by bobbins drawn from two stacks of reserve bobbins, a bobbin releaser for each stack movable in opposite directions to effect bobbin release, an actuator movable in one direction preparatory to a replenishing operation of the loom to effect lifting of a releaser and movable regularly in the opposite direction to effect lowering of a raised releaser, a depressing lug on each releaser normally below the path of said actuator when the latter moves in said opposite direction but movable into said path when the corresponding releaser is raised, a lifting lug pivoted to each releaser and movable into and out of the path of said actuator when the latter has said first motion, and means operated by said actuator when having successive movements in said one direction to effect movement of said pivoted lugs alternately into the last named path to cause alternate lifting movements of said releasers.

10. In a weft replenishing loom operating with a shuttle to be replenished by bobbins drawn

from two stacks of reserve bobbins, a bobbin releaser for each stack movable in opposite directions to effect bobbin release, an actuator movable along one path preparatory to a replenishing operation of the loom to effect lifting of the releasers and movable at regular intervals in the opposite direction along a second path to effect lowering of any raised releaser, a depressing lug on each releaser normally below the second path but liftable into said second path when the corresponding releaser is raised, a lifting lug pivoted on each releaser and movable into and out of the first path, means tending to move each lifting lug into said first path, and positioning mechanism for said lifting lugs positioned for movement by each releaser when rising and effective when moved to cause one of said lugs to move into and the other of said lugs to move out of the first path, said positioning mechanism and the means for said lifting lugs cooperating to reverse the relationship of said lifting lugs with respect to said first path for each movement of said actuator along the first path.

11. In a weft replenishing loom operating with two shuttle boxes and two shuttles therefor which are alternately active, a pair of stacks of reserve bobbins for each shuttle box, a pair of bobbin releasers for each pair of stacks, one releaser for each stack, a selector and actuator mechanism for said releasers corresponding to the active shuttle box, means effective upon depletion of weft in either shuttle to cause said mechanism to operate whichever releaser registers therewith of the pair of releasers corresponding to the depleted active shuttle, and means to cause said mechanism to operate alternately the releasers of either one of said pairs of releasers for successive depletions of the shuttle corresponding to the latter.

12. In a weft replenishing loom operating with two shuttles and shuttle boxes therefor which are alternately active, a pair of stacks of reserve bobbins for each shuttle, a pair of bobbin releasers for each pair of stacks, one releaser for each stack, a selector and actuator mechanism for said releasers, means operated by the shuttle boxes to register said mechanism with the pair of releasers corresponding to the active shuttle, means effective upon depletion of weft in either shuttle to cause said mechanism to move in a given direction to operate whichever releaser registers therewith of the pair of releasers corresponding to the depleted shuttle, and means operated by one of the releasers corresponding to the depleted shuttle to cause the other releaser corresponding to the depleted shuttle to be operated by the mechanism when the latter has its next movement in said given direction.

13. In a weft replenishing loom operating with two shuttles and shuttle boxes therefor which are active for alternate periods, a pair of stacks of reserve bobbins for each shuttle, a pair of bobbin releasers for each pair of stacks, one releaser for each stack, a selector and actuator mechanism for said releasers, means controlled by the shuttle boxes to register said mechanism with the pair of releasers corresponding to the active shuttle, means effective upon depletion of weft in either shuttle to cause said mechanism to move in a given direction to operate whichever releaser registers therewith of the pair of releasers corresponding to the depleted active shuttle, and means operated by said releasers to cause said mechanism to cooperate alternately with the releasers of either given pair of releas-

ers when the mechanism has successive movements in said given direction with respect to said given pair of releasers.

14. In a weft replenishing loom operating with two shuttles and two shuttle boxes therefor which are alternately active, a pair of stacks of reserve bobbins for each shuttle, a pair of bobbin releasers for each pair of stacks, one releaser for each stack and each releaser to have a movement to advance a bobbin of the corresponding stack toward replenishing position, a selector shifted in timed relation with the shuttle boxes to assume two operative positions, one position for each of said pairs of releasers, means operative when the selector is in either operative position to rock said selector in a given direction to give said movement to the releaser aligned with the selector if the shuttle corresponding to said operative position is exhausted of weft, and means to cause said selector when having successive rockings in said given direction for a given operative position to be aligned alternately with the releasers of the pair of releasers corresponding to the given position.

15. In a weft replenishing loom operating with two shuttles and two shuttle boxes therefor which are alternately active, a pair of stacks of reserve bobbins for each shuttle, a pair of bobbin releasers for each pair of stacks, one releaser for each stack and each releaser movable in one direction to initiate bobbin release and movable in the opposite direction to complete bobbin release, a selector shifting in timed relation with the shuttle boxes to assume two operative positions, one position for each of said pair of releasers, means operative when the selector is in either given operative position to rock said selector in one direction along either of two paths, depending upon the shifted position of the selector, if the shuttle corresponding to said given operative position is exhausted of weft, means to rock said selector at regular intervals in the opposite direction, a lifting lug movably mounted on each releaser, the lifting lugs of either given pair of releasers movable into and out of the corresponding path of said selector, and means to cause said lifting lugs of either given pair of releasers to move alternately into the corresponding path for successive rockings of the selector along the last named path, said selector operative thereafter to lower the depressing lug of a previously raised releaser to complete bobbin release.

16. In a weft replenishing loom operating with two shuttles and two shuttle boxes which are alternately active, a pair of stacks of reserve bobbins for each shuttle, a pair of bobbin releasers for each pair of stacks, one releaser for each stack and each releaser movable in one direction to initiate bobbin release and movable in the opposite direction to complete bobbin release, a selector shifting in timed relation with the shuttle boxes to move laterally to either of two operative positions, one position for each pair of releasers, means operative when the selector is in either operative position to rock said selector in one direction if the shuttle corresponding to said operative position is exhausted of weft to move a releaser of the pair of releasers corresponding to the depleted shuttle in said one direction, means to rock said selector at regular intervals in the opposite direction, a lifting lug pivoted to each releaser, and a lifting lug positioner for each pair of releasers and the corresponding lifting lugs, each positioner to be shifted by the corresponding releasers to move the

corresponding pair of lifting lugs alternately into operative position with respect to the selector when the latter is in the corresponding lateral position and has successive rocking movements in said one direction, said selector when moving in said opposite direction and aligned with a depressing lug of a previously raised releaser acting to lower the latter.

17. A bobbin releaser for a weft replenishing magazine operating with an actuator and a bobbin cradle, said releaser having an elongated body with provision at one end thereof for cooperation with the bobbin cradle, an operating member to cooperate with the actuator when in normal position and extended laterally from the releaser, a pivotal connection between the member and the releaser, and a stop on the member for engagement with the releaser, said member being counter-weighted to hold the stop against the releaser with the member in normal position.

18. A bobbin releaser for a weft replenishing magazine operating with an actuator and a bobbin cradle, said releaser having an elongated body with provision at one end thereof for cooperation with the bobbin cradle, an operating member to cooperate with the actuator when in normal position and extended laterally from the releaser, a pivotal connection between the member and the releaser, said member having a finger and a stop and being counter-weighted to hold the stop against the releaser with the finger extending laterally from the releaser in position for engagement by the actuator.

19. A bobbin releaser for a weft replenishing magazine operating with an actuator and a bobbin cradle, said releaser having an elongated body with provision at one end thereof for cooperation with the bobbin cradle, an operating member to cooperate with the actuator when in normal position and extended laterally from the releaser, a pivotal connection between the member and the releaser, said member having a finger and a stop and being counter-weighted to hold the stop against the releaser with the finger extending laterally from the releaser to a point displaced

with respect to the pivotal connection with reference to the length of the releaser.

5 20. A bobbin releaser for a weft replenishing magazine operating with an actuator and having a bobbin cradle, said releaser having an elongated body one end of which is adapted for cooperation with the cradle, a lifting lug pivoted to the releaser and having a laterally extending finger, and a counter-weighted stop on the 10 member opposite said finger with respect to the axis thereof for engagement with the releaser to hold the finger laterally with respect to the releaser for engagement by the actuator.

15 21. A lug positioner for a weft replenishing mechanism operating with a pair of bobbin releasing slides each having a lug pivoted thereto for cooperation with an actuator, said positioner having a pair of arms, one for engagement with each of said releasers, and a flexible member 20 secured to and extending from the positioner transversely of the arms for engagement with the lugs.

25 22. A lug positioner for a weft replenishing mechanism operating with a pair of bobbin releasing slides each having a lug pivoted thereto for cooperation with an actuator, said positioner having an axis of rotation and having an arm on each side of said axis, one arm for engagement with each of said releasers, and a flexible member 30 secured to said positioner and extending laterally from said arms to be located between said releasers for engagement with said lugs.

35 23. A lug positioner for a weft replenishing mechanism operating with a pair of bobbin releasing slides each having a lug pivoted thereto for cooperation with an actuator, said positioner having a pair of arms, one for engagement with each of said releasers, and a flexible member secured to and extending from the positioner transversely of the arms for engagement with the lugs, 40 said positioner also having provision to cooperate with a detent for holding said positioner in either of two positions.
